Specification for Design.

Patented May 25, 1920.

Application filed February 5, 1920. Serial No. 356,406. Term of patent 14 years.

To all whom it may concern:

Be it known that I, WILLIAM C. OWEN, a citizen of the United States, residing at Cleveland, in the county of Cuyahoga and State of Ohio, have invented a new, original, and ornamental Design for Tire-Casings, of which the following is a specification, reference being had to the accompanying drawing, forming part thereof.

Figure 1 is a plan view of a portion of a tire-casing showing my new design and Fig. 2 is a sectional view of the same on the line 2—2 of Fig. 1.

I claim:

The ornamental design for a tire-casing as shown.

WILLIAM C. OWEN.
